UNITED STATES PATENT OFFICE.

CHARLES F. BURGESS AND CARL HAMBUECHEN, OF MADISON, WISCONSIN.

BATTERY.

1,032,529.

Specification of Letters Patent. Patented July 16, 1912.

Application filed July 13, 1910. Serial No. 571,691.

To all whom it may concern:

Be it known that we, CHARLES F. BURGESS and CARL HAMBUECHEN, both citizens of the United States, residing at Madison, in the 5 county of Dane, State of Wisconsin, have invented certain new and useful Improvements in Batteries, of which the following is a specification.

The subject of the present application is 10 a battery of the general type ordinarily designated as a dry cell.

The novel features reside particularly in the special construction and coöperative relation of many of the component parts of 15 the cell whereby high efficiency and durability are attained.

The details of the invention are pointed out with particularity in the appended claims, for a better understanding of which, 20 reference may be had to the following detailed description taken in conjunction with the accompanying drawings.

In the drawings, Figure 1 is a sectional elevation of the battery. Fig. 2 is a fragmentary perspective view showing the painted top of the zinc container. Figs. 3 and 4 are details of the metal cap used on one end of the carbon electrode of the cell.

30 In the construction shown, the positive or zinc electrode comprises a sheet of zinc rolled into a tube or cylinder 1, and having a soldered seam 2 running lengthwise. After this tube has been soldered, it is 35 dipped in hot asphaltum paint so that one end of the tube is coated with asphaltum both outside and inside, for a distance of nearly an inch from the end of the tube. This paint serves to prevent local corrosion 40 of the zinc. The tube is then provided with a bottom 3, pressed into the shape of a cup and soldered in place. The terminal, or binding post 4 for the zinc electrode is soldered in place at the top end of the side 45 seam. We have found that by putting the terminal at this particular point, the zinc cup is materially strengthened, and furthermore, the presence, initially, of some solder under the asphalt paint at this point facilitates the soldering operation. The asphalt 50 on the outside of the can serves as a flux during the soldering operation. The bottom of the zinc cup is covered with a disk 5 of tar-paper. This paper is semi-soluble in 55 the zinc chlorid forming part of the battery mixture and changes to a gummy mass

capable of flowing down and filling any cracks or flaws in the soldered joint beneath. The sides of the cup are lined with a very porous paper cylinder or wrapping 60 6, having its lower end folded inward at 7 to overlap the edge of the tarred paper disk. A porous paper bottom 8 covers the in-turned edges of the paper tube 6.

The negative or carbon electrode of the 65 cell comprises a cylindrical carbon rod 9 provided at its top with a brass cap 10, through which current may be conducted from the electrode. In constructing these electrodes, the carbon rods are soaked for 70 about a minute in hot paraffin, before the brass caps are put in place. The entire electrode is immersed in the paraffin so that it is impregnated throughout its entire length with a moisture-resistant material. This 75 not only prevents the creeping of electrolyte upward to the metal terminal, but it also excludes substantially all moisture from the rod when the cell is assembled, thereby avoiding the difficulties incident to 80 the use of rods which might from day to day vary in their moisture absorbing power. Also, by having the electrode uniformly impregnated, there is no danger of putting the metal terminal on an unimpregnated end. 85 The brass cap 10 is coated with paraffin both inside and outside by dipping, and then is put on the carbon rod with a driving fit. This layer of paraffin on the brass cap protects the cap from incipient corrosion while 90 the active mixture is being tamped into place within the cell. In order to avoid the defective connection which might arise if the carbon rod were a trifle under size, the brass cap is provided with a single indentation 95 11 which forms on the inside of the cap a sort of shoulder capable of yielding sufficiently to allow the cap to be pressed on the rod. This shoulder collapses as the cap is forced on the rod, but is resistant enough 100 to insure intimate contact between the cap and rod, even though the rod is slightly below normal size. The indentation is made with a tool having a face so beveled that the shoulder presents an inclined surface, and 105 will slip over the end of the carbon rod without tearing or chipping the carbon.

In assembling the cell, the carbon rod is supported in its normal position with respect to the zinc cup, and a moist and active mixture of carbon, manganese dioxid, ammonium chlorid and zinc chlorid is tamped 110

into place to a level considerably below the top of the zinc cup. The paper lining 6 is then trimmed off at its upper end to present a smooth upper edge. The lining 6 is high enough to overlap the band of paint at the top of the zinc cup and is not bent over or crimped, but lies directly in contact with the coated top of the cup. A layer 12 of porous material, such as sand mixed with 5 sawdust is then put on top of the active mixture and to a level slightly below the upper edge 13 of the paper lining. This sand and sawdust forms a moisture-absorbing medium capable of taking up water 10 when the active mixture is too damp and giving up moisture as the active mixture needs it. The absorbing medium thus serves as a sort of regulator to govern the wetness of the active material. This porous layer 15 is in intimate contact with the active material. This arrangement facilitates the easy 20 passage of water from one to the other. The cell is sealed by a layer of pitch 14 poured in until it fills the cell to the top 25 of the zinc cup. This pitch is in direct contact with the sand and sawdust, and forms a sort of double seal at the upper edge of the paper lining, excluding substantially all 30 air and protecting the upper edge of the zinc cup from corrosion. The lining of asphalt paint initially provided on the zinc cup assists in securing intimate contact between the pitch and the zinc, and coöperates with the pitch in limiting local corrosion. The 35 layer of paraffin on the metal cap 10 facilitates the making of a good seal about the cap.

Having described our invention, what we claim as new, and desire to secure by Letters Patent, is:—

1. In a primary battery, a zinc container having a soldered seam and a terminal for said container soldered in place at said seam.
2. In a primary battery, a zinc electrode 45 serviceable as a container and having an end portion painted inside and out with asphaltum paint, said electrode having a soldered seam and a terminal soldered to said electrode at said seam.
3. In a primary battery, a zinc electrode serviceable as a container and having a soldered seam, and tar-paper over said seam.
4. In a primary battery, a zinc container having a bottom soldered in place, a tar- 55 paper disk over said bottom, and a porous paper lining for said container, said lining having its upper edge trimmed to lie directly in contact with said container.
5. In a primary battery, a zinc container 60 having a bottom soldered in place, a tar-paper disk over said bottom, a porous paper lining for said container, said lining having its upper edge trimmed to lie directly in contact with said container and having its 65 lower edge folded inward to overlap the

edge of said tarred paper disk, and a porous paper bottom covering the inturned edge of said porous lining.

6. In a primary battery, the combination 70 of a cylindrical zinc container, an asphaltum coating around the top of said container, a tubular paper lining for said container having its top edge trimmed to lie in contact with the coated top of said container and having its lower edge crimped inward at the bottom of said container, a porous paper bottom covering the inturned edge of said tubular lining, an active mixture in said container, a layer of porous inert material above said mixture and below the top 75 of said paper lining and a pitch seal at the top of said container where it is coated with asphaltum, said pitch seal contacting directly with the upper trimmed edge of said lining and also contacting with said layer 80 of porous inert material.

7. The combination of a container, a solid carbon rod therein which has been impregnated throughout its entire length with a moisture-repelling medium, a thin metal cap 90 inclosing one of the impregnated ends of said rod, a moisture-resisting coating on said cap, a moist active mixture in contact with said rod, and a pitch seal enveloping said coated cap and closing the end of said 95 container.

8. In a primary battery, the combination 100 of a cylindrical zinc container having a bottom soldered in place, an asphaltum coating around the top of said container, a tar-paper disk placed above said bottom, a tubular paper lining for said container having its top edge trimmed to lie in contact with the coated top of said container and having its lower edge contacting with said tar-paper 105 disk, an active mixture in said container, a layer of porous inert material above said mixture and below the top of said paper lining, a carbon rod impregnated throughout its length with paraffin and contacting with 110 said active mixture, a thin sheet metal cap pressed into place on the upper end of said rod, a moisture-repelling coating on said cap, and a pitch seal at the top of said container where the zinc is coated with asphaltum, said pitch seal contacting directly with the upper trimmed edge of said lining and also contacting with said layer of porous 115 inert material.

9. In a primary battery, the combination 120 of a cylindrical zinc container, an asphaltum coating around the top of said container, a tubular paper lining for said container having its top edge trimmed to lie in contact with the coated top of said container and having its lower edge folded inwardly, a porous paper bottom covering the inturned edge of said porous lining, an active mixture in said container, a layer of porous inert material above said mixture and below the 125 130

top of said paper lining, a carbon rod impregnated throughout its length with paraffin and contacting with said active mixture, a thin imperforate sheet metal cap 5 pressed into place on the upper impregnated end of said rod, and a pitch seal at the top of said container where the zinc is coated with asphaltum, said pitch seal contacting directly with the upper trimmed edge of 10 said lining and also contacting with said layer of porous inert material.

10. In a primary battery, the combination of a zinc electrode adapted to serve as a container, and having a soldered side seam with 15 a terminal put on at said seam, said electrode having a bottom soldered in place, a tar-paper disk placed above said bottom, a porous lining for said container having its upper edge lying in contact with said con-

tainer, an active mixture packed in said container within said lining, a layer of porous material above said mixture and contacting directly therewith, the top of said porous layer being below the upper edge of said porous paper lining, a carbon rod contacting with said active mixture, said rod having a metal cap tightly engaging its upper end, and a layer of pitch forming a seal about said metal cap and about the upper edge of said paper lining.

In witness whereof, we have hereunto set our hands this 7th day of July, A. D. 1910.
